[57] CLAIM

The ornamental design for an air compressor for tire inflation, as shown and described.

DESCRIPTION

FIG. 1 is a top perspective view of an air compressor for tire inflation showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and
FIG. 8 is a top perspective view thereof, the broken-line showing of the tubing being for illustrative purposes only and forming no part of the claimed design.
